Nº 17,906,

UNITED STATES PATENT OFFICE.

ELBRIDGE WEBBER, OF GARDINER, MAINE.

SHINGLE-MACHINE.

Specification of Letters Patent No. 17,906, dated July 28, 1857.

To all whom it may concern:

Be it known that I, ELBRIDGE WEBBER, of Gardiner, in the county of Kennebec and State of Maine, have invented a new and useful Improvement in Shingle-Machines; and I do hereby declare that the following is a full, clear, and exact description of the construction and operation of the same, reference being had to the annexed drawing, 10 forming part of this specification, in which—

Figure 1 is a top view of the machine. Fig. 2 is a vertical section on line x x . Fig. 3 is a vertical section on line y y . Fig. 4 is a plan view of the left hand portion of main 15 frame, with carriage removed. Fig. 5 shows the mode of giving pulley g' a motion of translation. Fig. 6 is a top view of vibrating frame by which the taper of the shingle is regulated.

20 Similar letters denote the same part.

The character of machine constituting the subject of my invention is that in which the shingles are formed by sawing.

The nature of the invention consists in 25 certain devices hereinafter to be set forth for automatically regulating the movement of the carriage, and for so presenting the bolt to the saw as alternately to cut the points of the shingles from opposite ends 30 thereof: the details of construction and operation being as follows:

In the drawing A is the main frame and Z the carriage, the latter made to traverse 35 in direction of arrow by the meshing of pinion F with rack 10. This pinion F has a loose connection with shaft n , and becomes attached thereto, when clutch F' has the position shown in Fig. 4. The lever d moves the said pinion so as to mesh with, or separate from the clutch. The said lever d is 40 attached to a draw rod c' , to which is hung a weight w , whose tendency is to produce the closing of the clutch F' and the consequent movement of pinion F with shaft n . 45 This rod is also connected with a lever C, for operating lever d by hand.

Upon the side of a branch of lever d , is a ratchet o , attached to lever d by a pin o' , so that pressure against any of the teeth 50 of this ratchet in direction of arrow will separate the clutch F' and pinion F, and leave the carriage Z free to be drawn back by the action of weight w' , attached to a cord passing over sheave g' . The depending 55 stud w , of the carriage is designed to effect this operation; and the extent of the move-

ment of the carriage in direction of the arrow, will be governed by the number of teeth of ratchet o , which the said stud can pass over before contact. To govern this amplitude of movement, there is a shaft L passing across the machine (Fig. 3), on which is a pinion p , meshing with a rack E (Fig. 2). A slot in this rack passes over a pin in the free extremity of ratchet o , so that the 60 elevation or depression thereof is readily effected by turning shaft L. This regulation of the forward movement of the carriage Z renders another adjustment necessary. That is the preservation of a constant descent of 70 weight w' under all circumstances. This is effected by attaching the journal of sheave g' to a rack slide g (Fig. 5); which rack meshes with a pinion p' on shaft L (Fig. 3), thereby causing the sheave g' to be adjusted to the 75 run of the carriage Z.

There is a bent lever m , at the foot of the frame, notched and weighted as shown in Fig. 2. This notch catches pin m' on slide rod c' , when by the opening of clutch F' 80 this rod is drawn forward, thus permitting weight w' to draw the carriage back. The striking of the carriage frame against the upright branch of this lever, at the termination of this backward movement, releases 85 pin m' , and permits weight w to act, and operating lever d close clutch F', and permit the carriage to again move forward.

The head block 5' moves across the carriage Z on the frame 2', and is fed up by 90 means of screw S and depending nut n' , by means of lever k , pawl k' and ratchet k'' , and projecting bench b' . This nut is raised from the screw by means of spring 3 and hand lever 3', to allow said head block to 95 slide back upon frame 2'.

The frame 2' is attached to the carriage frame by a bolt f , about which it is free to vibrate. This movement is produced in the following manner: A pin 11' depending 100 from a portion of frame 2' enters an oblique slot in slide piece 11, as seen in Fig. 6. This slide piece has a pin embraced between the irregular wheels 12, which from the rotation of said wheels produces a reciprocating 105 motion of the slide piece 11. When this movement of piece 11 takes place the slot and pin connection with frame 2', will cause a vibration of said frame about bolt f . This causes the bolt to be so presented to the saw 110 that the butts and points of the shingles shall alternate. The rotation of irregular

wheels 12 is produced by ratchet 14', lever 14, pawl 16, and bench b'' .

The wheels 12 are adjustable upon their shaft, so as by their greater or less opening 5 to regulate the amplitude of reciprocation of bar 11, and the consequent vibration of head block. This is necessary in order that the machine may be adapted to the production of shingles of different lengths. The 10 bolt is held between dogs 6, 6, attached to two pinions 7, 7, at the extremities of levers 7', 7'. One of these levers is slotted, and the other has a pin entering in the slot, so that both are moved by power applied to 15 lever handle H. The pinions mesh in racks in the floor of the head block and thus move the dogs 6, as desired and firmly hold the bolt when inserted between the teeth of the dogs. The saw X is driven by power applied 20 to pulley X', while motion is communicated to shaft n as shown in Fig. 1.

As the carriage Z is drawn back by weight w', levers k and 14 press against their respective benches b' b'' , and moving the 25 ratchets k'' and 14', feed the head block forward and give the necessary vibration to the frame 2', and through it to the head block. The striking of the carriage against the lever m, closes the clutch F' as above de-

scribed and produces the forward movement of the carriage a sufficient distance for the length, of bolt, the amplitude of which is regulated as before described. The operation is thus continued automatically until the bolt is consumed, the butt and points of 35 successive shingles being cut from opposite extremities of the bolt.

What I claim and desire to secure by Letters Patent is—

1. The combination of the vibrating frame 40 2' with the obliquely slotted slide piece 11 and the cam wheel 12, arranged and operating substantially as, and for the purpose set forth.

2. The relative adjustment of ratchet o 45 and sheave g' , substantially as and for the purpose specified.

3. The arrangement of the pinions 7 7 with levers 7' 7' and dogs 6 6 as herein set forth. 50

In testimony whereof, I have hereunto signed my name before two subscribing witnesses.

ELBRIDGE WEBBER.
